Term of patent 14 years

Int. Cl. D26—02

U.S. Cl. D48—20

FIG. 1 is a side perspective view of a light for special effects, including entertainment, stage lighting, and advertising embodying my new design;

FIG. 2 is a perspective view of the side opposite that shown in FIG. 1;

FIG. 3 is a bottom plan view thereof;

FIG. 4 is an enlarged, fragmentary elevational view in cross section of the symmetrical lenticular elements comprising the top of the light, the sectional view being identical on both lines designated 4—4 of FIG. 1.

FIG. 5 is a front perspective view thereof;

FIG. 6 is a rear perspective view thereof.

The dominant features of my design reside in the portions shown in full lines.

I claim:

The ornamental design for a light for special effects, including entertainment, stage lighting, and advertising, substantially as shown and described.
